NARROWING MECHANISM FOR KNITTING MACHINES

Sadami Imen, Komeno-cho, Naka-ku,
Nagoya, JapanApplication December 17, 1934, Serial No. 757,950
In Japan December 28, 1933

2 Claims. (Cl. 66—70)

This invention relates to a mechanism for automatically effecting so-called "decreasing" of the loops of thread in flat or Lamb type knitting machines having two needle beds or rows of needles sloping at an angle of nearly 90°. The object of the invention is to provide a knitting machine of such type in which the "decreasing" of the loops of thread can be automatically and accurately effected in a simple manner.

10 In the accompanying drawings in which one embodiment of the invention is shown by way of example:—

Figure 1 is a front view of the machine according to this invention;

15 Figure 2 is a side elevation thereof;

Figure 3 is an enlarged front view in detail; Fig. 3a is a sectional view showing the manner of slidably mounting racks for actuating knitting needles;

20 Figure 4 shows in section a part of a double shaft shown in Figure 3;

Figure 5 is an enlarged side view in detail;

Figure 5a is an enlarged view of a detail;

25 Figure 6 is a detail showing one of the cam controlled reciprocating rods;

Figure 7 is a detail showing the device for actuating transfer needles;

Fig. 7a is a section taken on line 7a—7a of Fig. 7;

30 Figure 8 is a view diagrammatically showing the relation between the transfer needle and the knitting needle;

Figure 9 is an enlarged view showing the top of Figure 8;

35 Figure 10 is a section taken along line X—Y of Fig. 9;

Figure 11 is a detail showing the under side of a transfer needle;

Figure 12 is a detail showing a device for actuating a screw-threaded shaft;

40 Figure 13 is a rear elevation thereof;

Figures 14 and 15 are front and side views showing the coupling mounted on the cam shaft;

45 Figures 16 and 17 are details showing a latching bolt and actuating block therefor used in said coupling;

Figures 18 to 22 show the shape of various cams controlling the motion of the device according to this invention;

50 Figure 23 is a diagram showing in order the operation of said cams.

Referring to the drawings, mounted upon the frame 1 is a main shaft 2, to which is operatively connected a shaft 3 through an intermediate driving shaft 3'. To said shaft 3 are fixed a

crank 4, an eccentric disc 5, and a sprocket wheel 6. Through an intermediate lever 7 and links 8 and 9, the end of the crank 4 is operatively connected to a main rocking lever 10. An eccentric strap rod 11 carries at its free end a pawl 12. Provided at the top of the right-hand side (Fig. 1) of the machine is a pattern mechanism comprising a roller 13 and a pattern belt 15 surrounding said roller and carrying a plurality of feelers 14 arranged at desired intervals. A rotary weight 16 is provided for the purpose of maintaining the pattern belt 15 in tension. On one side of the roller 13 is mounted a ratchet wheel (not shown) adapted to be rotated intermittently by means of the pawl 12 in accordance with the movement of the rod 11. To the upper end of a bracket 17 is pivoted a lever 18 which is adapted to be engaged and lifted by the feelers 14. The free end of the lever 18 is connected by means of a link 19 to a reciprocating rod 21, the latter 20 carrying at its lower end an arc-shaped actuating block 20. (Figs. 14 and 16.) Said block 20 is obliquely cut at both ends as shown in Figure 16, and is inserted in an annular groove 24 formed in the coupling disc 23 which is fixed on the rotating shaft 22. The disc 23 is formed with a bore 24', and in said bore is inserted a latching bolt 25 provided with a recess 25' as shown in Figures 15 and 17. At the outer end, the bolt 25 is pressed inwardly by a spring 26 and the inner end thereof projects into a hole 27' formed in a sprocket wheel 27 which is loosely mounted on the shaft 22. Said sprocket wheel 27 is driven from the sprocket wheel 6 on the shaft 3 by means of a driving chain 28. There is provided suitable 30 means (not shown) influenced by the rotation of the cam shaft 22 for stopping the motion of the main rocking lever 10 during the rotation of said shaft 22.

At the end of the rotating shaft 22 there are secured a plurality of cams A, B, C, E and D, with which respectively engage reciprocating rods A', B', C', E' and the short arm D' of a bell crank lever 31, each by means of an antifriction roller 29. In order to ensure good engagement, each 45 reciprocating rod is pulled downwardly by means of a spring 30 as shown in Figure 6, and the lever 31 is provided with an extension 31' which is pulled leftwardly (in Figure 1) by a spring 32.

Mounted on the top of the frame are rails 33 50 (Figs. 1 and 5), on each of which is mounted a carriage 35 for actuating knitting needles 34 and also a base 36 supporting a transfer needle mechanism. The carriage 35 is operatively connected through a link to the upper end of the main 55

rocking lever 10 in usual manner. The base 36 is operatively connected through a link 37 to the free end of the bell crank lever 31. On the base 36 is secured a guide block 38, having a guide way (Figs. 3, 5, and 7), with which engages a slide 39. The upper surface of said slide 39 is formed with a rack 39'. Secured at right angles to the slide 39 is a guide rail 40. A reciprocator 41 engages with said guide rail 40, and it is normally pulled downwardly and rearwardly by means of springs 42 and 43. To one side of the guide block 38 is secured a guide plate 44 which engages with a pin 45 secured on one side of the reciprocator 41. Said guide plate 44 is so shaped that, when the slide 39 is retracted with the rail 40 and the reciprocator 41, the latter is moved upwardly along the rail 40, the pin 45 on the reciprocator ascending along the front inclined edge of the guide plate 44. At the front of the lower end of the reciprocator 41 there are secured a plurality of transfer needles 46, and rearwardly thereof a brush 47 is secured. In Figure 7a four transfer needles 46 are shown, so that decreasing of loops is effected on four needles. This is for the purpose of producing a neat appearance of the edge of the knitted article on which decreasing or narrowing has been done. Provided also on the base 36 is a bearing 48 (Figure 3), in which is journaled a shaft 50 having a fixed gear 49 at its one end. Said gear 49 meshes with an intermediate gear 51 which in turn meshes with the rack 39'. The other end of the shaft 50 is journaled in bearings 52 and 53, and between said bearings is a gear 54 which is slidable but non-rotatable relative to the shaft 50. For this purpose, the shaft 50 is splined as at 55, and the gear 54 is mounted thereon by means of a key 56. The gear 54 meshes with a rack 57 formed on the reciprocating rod C' associated with the cam C.

Near the top of the frame 1, a screw-threaded shaft 58 is rotatably mounted, which shaft having a fixed ratchet wheel 59 at its one end (Figs. 3, 5, 12, and 13). Loosely mounted on said shaft 58 adjacent said ratchet wheel is a gear 62 having an arm 61 which carries a pivoted pawl 60. The gear 62 meshes with a toothed rack 63 on the reciprocating rod E' associated with the cam E. The pawl 60 is normally maintained in engagement with the ratchet wheel 59 by means of a spring 64 connected to the gear 62.

65 is a needle bed adapted to traverse to and fro according to the rotation of the screw-threaded shaft 58, and it is provided with a plurality of recesses 66 through which knitting needles project. Beneath said needle bed 65 is a double shaft consisting of an inner shaft 67 and an outer hollow shaft 68. (Figs. 3, 4, and 5.) At the ends of the inner shaft 67 are mounted gears 69 and 70, and at the ends of the outer shaft 68 are mounted gears 71 and 72. The gears 70 and 72 respectively mesh with toothed racks 73 and 74 formed on the upper ends of the reciprocating rods A' and B' respectively associated with the cams A and B. The gear 69 on the other end of the inner shaft 67 meshes with a toothed rack 75 having a butt 75' at its rear end and adapted to advance the knitting needles 34. For the purpose, the butt 75' of the rack 75 engages with the rear faces of the butts of the needles 34. The gear 71 on the same end of the outer shaft 68 meshes with a toothed rack 76 having a butt 76' at its rear end and adapted to retract the knitting needles 34. Said racks 75 and 76 are slidably mounted in slots formed in a block secured to a

fixed part of the frame as best shown in Figure 3a.

As shown in Figure 5, there are two needle beds 65 and both are operatively connected to the shaft 58, and both are equally provided with 5 knitting and transfer needles and actuating means therefor as hereinbefore described. Although the cams and reciprocating rods actuated thereby are shown only for the left hand needle bed 65 in Figure 5 for the sake of clearness, it 10 is to be understood that actually another set of quite similar cams and reciprocating rods is provided also for the right hand needle bed, so that decreasing of loops is effected on both needle beds.

For the purpose, the butt 75' of the rack 75 15 engages with the front faces of the butts of the needles 34. As shown in Figure 3, the racks 75 and 76 are horizontally spaced, but the butts 75' and 76' thereof are brought into same vertical plane, as shown in Fig. 5a, so that the butts 75' 20 and 76' alternately act upon the same needles, one pushing the needles forwardly and the other pushing the needles rearwardly. As shown in Fig. 5a, the racks 75 and 76 are designed to operate four needles at a time.

The operation of this invention is as follows:— The main shaft 2 drives the shaft 3 and, as the latter rotates, the main rocking lever 10 is actuated through the links 9 and 8 and it gives reciprocating sliding movements to the carriage 35, whereby operating the knitting needles as in the usual manner. At the same time, the pawl 12 which is associated with the eccentric disc 5 intermittently rotates the roller 13 with the pattern belt 15, and a feeler 14 thereon engages with the projection on the lever 18 and lifts the latter, whereby the link 19 and the reciprocating rod 21 carrying the actuating block 20 are lifted. Whereupon, the latching bolt 25 under the influence of the spring 26 is pressed inwardly and 35 engages with the hole 27' in the sprocket wheel 21, whereby the latter is operatively connected to the shaft 22 through the coupling disc 23, and the shaft 22 is rotated. When the latching bolt 25 again comes to the uppermost position 45 after having completed one revolution, it is disengaged from the sprocket wheel 27 by the action of the actuating block 20 which has already returned into the groove 24, the lever 18 having returned to the normal lowered position, whereby the coupling disc 23 is disengaged from the sprocket wheel 27, and its rotation ceases. Thus, it will be seen that the cam shaft 22 performs only one rotation at a time, and during such rotation the various cams thereon automatically 55 control the mechanism for decreasing the number of loops of thread.

The cam D controls, through the lever 31 and the link 37, the movement of the base 36 carrying the needle transfer mechanism.

The cams A and B respectively control the rotation of the inner and outer shafts 67 and 68 for projecting and retracting the knitting needles 34.

The cam C controls the rotation of the shaft 58 for actuating the slide 39 through the gears 49 and 51, thereby controlling the movement of the transfer needles 46.

The cam E controls the rotation of the gear 62 for rotating the screw-threaded shaft 58, thereby shifting the needle beds 65 for one needle interval.

The so-called decreasing operation according to this invention is accomplished by the mecha- 75

nism actuated by the combined control of said various cams in the following manner:—

Refer mainly to Figure 23. As the cam shaft 22 rotates, the base 36 moves from the predetermined rest position to the position at which "decreasing" should be effected. (The cam D, from point *a* to point *b*.) By this time, the cam A has already acted upon the rack 75, and that knitting needle which is to be "decreased" or eliminated is lifted for some extent. At the point *c* (in Fig. 23), the needle 34 is advanced to the position *P* shown in Figure 7. At this moment, the spoon-like latch 34' turns back. (But, the transfer needle 46 is yet in a rear and upper position.) Such movement of the knitting needle is effected by the movement of the cam A, point *c*. Next, the transfer needle 46 carried by the reciprocator 41 advances along the guide plate 44, and the tip of the transfer needle 46 comes beneath the turned latch 34' as just shown in Figure 7. This is effected by the cam C moved to point *c'*. Next, the knitting needle 34 and the latch 34', together with the transfer needle 46, further advance to the position as shown in Figure 9 (point *d* in Fig. 23). The loop of thread is disengaged from the latch 34' and is engaged by the transfer needle. This is effected by the cams A and C, point *d*. The knitting needle is further advanced so as to have the loop entirely disengaged from the latch 34' as shown in position *Q* in Figure 8. This is effected by the cam A, point *e*. Next, the knitting needle is retracted to the position *R* in Figure 8. This is effected by the cam B, point *f*. The toothed rack 75 starts to be lowered. This is effected by the cam A. When the toothed rack 75 is brought near the upper rest position by the cam B, the needle bed 65 is shifted transversely for one needle interval. This is effected by the cam E, from point *g* to point *h*. Consequently, one knitting needle is eliminated, and the needle carrying the next loop is advanced. In the position *R* in Figure 8, the latch 34' is closed, but upon the advance movement of the needle the latch 34' is opened by the action of the brush 47 (Fig. 7), and it receives the loop from the transfer needle. This is effected by the cam A, from point *i* to point *j*. The transfer needle 46 is then retracted leaving the loop upon the knitting needle which has just advanced. This is effected by the cam C, from point *k* to point *l*. Then, the toothed rack 75 is lowered or retracted to the rest position. This is effected by the cam A, from point *m* to point *n*. Thus, the so-called "decreasing" operation is effected automatically. After finishing said operation, the base 36 is returned to the above-mentioned rest position. This is effected by the cam D, from point *n* to point *a*.

60 The time at which the above-mentioned "decreasing" operation is effected is determined by the pattern belt 15, and by suitably designing the pattern belt it is possible according to this invention to effect the "decreasing" automatically and accurately at desired intervals.

Although the knitting machine according to

this invention is designed for use in knitting tubular fabric, it can be used also for knitting thicker plain fabric, knitting on both needle banks simultaneously, as is usual in existing flat type knitting machines.

5

What I claim is:—

1. A mechanism for automatically decreasing the number of loops in flat type knitting machines comprising a cam shaft, a cam on said shaft controlling the advancing movement of the knitting needles, a second cam on said shaft controlling the retractive movement of said knitting needles, a third cam on said shaft controlling a transfer needle, a transfer needle mechanism, a base supporting said mechanism, a fourth cam on said shaft controlling the shift of said base, a needle bed, a fifth cam on said shaft controlling said needle bed, a coupling upon said shaft, means including a pattern for actuating said coupling so as to rotate said shaft a single revolution, a reciprocator carrying said transfer needle controlled by said third cam so as to impart thereto a movement parallel relative to the base and at right angles to the movement of the knitting needle, said cams being so constructed that upon rotation said base is first shifted by said fourth cam from the predetermined rest position to a position at which "decreasing" should be effected, then the tip of the transfer needle is brought below the latch of the knitting needle by the third cam, then said transfer needle and knitting needle are advanced together under the influence of the first and third cams, then said knitting needle only is retracted under the influence of the second cam, transferring the loop from said knitting needle to said transfer needle, then the knitting needle is shifted transversely relative to the transfer needle under the influence of the fifth cam, then next the knitting needle is advanced under the influence of the first cam to the position of the loop that has been just transferred, then the transfer needle is retracted under the influence of the third cam, thereby transferring the loop to the knitting needle just advanced, and then the base is returned to the first mentioned rest position under the influence of the fourth cam.

2. A mechanism for automatically decreasing the number of loops in flat type knitting machines as set forth in claim 1 in which said coupling comprises a coupling disk having an annular groove fixed to said cam shaft, an actuating block obliquely cut at both ends located in said groove, a latching bolt movably mounted in said coupling disk, a sprocket wheel loosely mounted on said shaft having a hole therein in which said latching bolt is normally inserted, the arrangement being such that when said actuating block is lifted said sprocket wheel is operatively connected to said shaft but upon completion of one rotation of said shaft said latching bolt is disengaged from said sprocket wheel provided said block has been lowered whereby the driving connection is disengaged.

SADAMI IMON. 65
